(57) **CLAIM**

The ornamental design for a cutting tool, as shown and described.

DESCRIPTION

FIG. 1 is a front view of a cutting tool showing my new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a first perspective view thereof;

FIG. 8 is a second perspective view thereof;

FIG. 9 is a third perspective view thereof;

FIG. 10 is a fourth perspective view thereof;

FIG. 11 is an enlarged view of the portion 11 in FIG. 1;

FIG. 12 is an enlarged view of the portion 12 in FIG. 2;

FIG. 13 is an enlarged view of the portion 13 in FIG. 3;

FIG. 14 is an enlarged view of the portion 14 in FIG. 4;

FIG. 15 is an enlarged view of the portion 15 in FIG. 5;

FIG. 16 is an enlarged view of the portion 16 in FIG. 6;

FIG. 17 is an enlarged view of the portion 17 in FIG. 7;

FIG. 18 is an enlarged view of the portion 18 in FIG. 8;

FIG. 19 is an enlarged view of the portion 19 in FIG. 9;

FIG. 20 is an enlarged view of the portion 20 in FIG. 10;

FIG. 21 is an enlarged view of the portion 17 in FIG. 7, where areas shaded in gray form no part of the claimed design;

FIG. 22 is an enlarged view of the portion 18 in FIG. 8, where areas shaded in gray form no part of the claimed design;

FIG. 23 is an enlarged view of the portion 19 in FIG. 9, where areas shaded in gray form no part of the claimed design;

FIG. 24 is an enlarged view of the portion 20 in FIG. 10, where areas shaded in gray form no part of the claimed design; and,

FIG. 25 shows a cutting tool in an environment of use thereof.

(Continued)

The broken lines in the drawings depict portions of the cutting tool that form no part of the claimed design. The gray shaded portion forms no part of the claimed design. The dot-dash broken lines depicting the areas of enlargement form no part of the claimed design. The additional broken lines in FIG. 25 depict environment that forms no part of the claimed design.

1 Claim, 13 Drawing Sheets
